Primary Examiner — Kelley A Donnelly*(74) Attorney, Agent, or Firm* — Guy V. Manning**CLAIM**

The ornamental design for a lap desk with workpiece clip, as shown and described.

DESCRIPTION

FIG. 1 is an elevated, front, left perspective view of a new design for a lap desk with workpiece clip;

FIG. 2 is a top plan view of the new design of FIG. 1;

FIG. 3 is a bottom plan view of the new design of FIG. 1;

FIG. 4 is a front elevational view of the new design of FIG. 1;

FIG. 5 is a rear elevational view of the new design of FIG. 1;

FIG. 6 is a right side elevational view of the new design of FIG. 1; and,

FIG. 7 is a left side elevational view of the new design of FIG. 1.
